FIREPLACE HEATER

Ross W. Snyder, Bradenton, Fla., assignor of
one-half to Robert F. Sharp, Bradenton, Fla.

Application November 11, 1935, Serial No. 49,315

6 Claims. (Cl. 126—121)

This invention relates to improvements in fireplace heaters wherein a hollow heating element is utilized in connection with an open fireplace for heating air and delivering it to a room.

5 The primary object of my invention is to provide an improved and scientifically designed heater for using some of the formerly wasted heat developed in an open fireplace, by causing air heated thereby to flow into a room, thereby 10 greatly improving the efficiency of the fireplace for heating purposes.

Another object is to provide an improved device 15 associated with an open fireplace for directing a current of heated air into a room, to supplement the heat normally radiated from the fireplace and improve the ventilation of the room.

A further object is to provide a device, serving 20 as a form about which the brickwork of an open fireplace may be built, for heating and delivering air to a room.

A still further object is to provide an improved device for utilizing some of the heat generated in an open fireplace, and which is normally wasted, by heating air drawn from inside and/or outside 25 of a room and delivering said air into said room.

Another object of my invention is to provide a hot air heater associated with an open fireplace and so formed that the flue gases from said fireplace pass therethrough, the flue portion 30 gradually decreasing in area upwardly, in order to maintain a practically constant velocity of flow of flue gases, said flue being surrounded by an air-heating compartment or conduit which gradually expands in area upwardly in accordance 35 with the normal expansion of the air being heated, so that the velocity of flow of heated air through the heater is substantially constant and said air tends to force itself out of the upper end of the conduit.

40 With the foregoing and various other objects in view, the invention desirably consists of certain novel features of construction and operation, as will be more fully described and particularly pointed out in the specification and illustrated in the drawings.

Referring to the drawings which illustrate an embodiment of my invention, and wherein like reference characters are used to designate like 50 parts:

Figure 1 is a front elevational view of one embodiment of my fireplace heater, with the brick-work removed from a portion thereof in order to more clearly show the construction.

55 Figure 2 is a vertical sectional view on the line

2—2 of Figure 1, looking in the direction of the arrows.

Figure 3 is a top plan of my fireplace heater with the brickwork removed.

Figures 4, 5 and 6 are horizontal sectional views 5 on the correspondingly numbered lines of Figure 1, looking in the direction of the arrows and showing the heater with the brickwork removed.

Figure 7 is a vertical sectional view corresponding to Figure 2, but showing the intermediate 10 section of the heater detached from the associated end sections, brickwork and insulation.

Figure 8 is a bottom plan of the intermediate 15 section of the heater shown in Figure 7.

Figure 9 is a fragmentary side elevational view 20 of the lower portion of the complete heater, as shown in Figure 1, said view especially showing the details of the regulating shutter or damper for the air inlet from the room.

Referring to the drawings illustrating a desirable embodiment of my invention, it will be seen 25 that my invention comprises a heating device, about which a brick or masonry open fireplace may be built, generally designated by the reference character 1 and desirably formed of metal, for example, cast iron. For convenience in manufacture and assembly, the device is desirably formed in a plurality of parts, such as a lower or fireplace forming part 2, an intermediate or main heat transfer part 3 and an upper hood or hot air discharge part 4. The parts are desirably formed for convenient assembly obviating leakage, and for that purpose the lower portions 30 of the intermediate and upper parts 3 and 4 desirably have depending flanges 5 and 6 which telescope with the upper edge portions of the walls of the sections therebelow, as shown most clearly in Figure 2. In this way, the parts are readily assembled in tight-fitting relation without danger of any appreciable leakage. If desired, the telescoping joints may be sealed by insulating packing, as will be understood.

The parts of my heater are not only desirably formed for convenient assembly, but the outside 45 surfaces thereof are desirably generally rectangular, and the main heat transfer part of generally uniform horizontal cross-section, so that brickwork or masonry 7 can be conveniently placed therearound. During the development of the heater being described it was found easier to build the fireplace and chimney brick 7 around such a heater than to build a fireplace and chimney, without the heater to serve as a form.

The fireplace heater 1 of my invention is 50 designed for great efficiency in the utilization of the

heat developed in the fireplace, as when burning logs of wood 8 on andirons 9, and for that purpose desirably involves the following features:—

It is well known that as air or gas cools it contracts in volume in accordance with scientific laws. This is because the product of the pressure and volume of a gas divided by the absolute temperature is a constant. Inasmuch as the pressure of the flue gases can be assumed as substantially constant, the volume will vary inversely as the absolute temperature. Therefore, if such gases are conducted in a flue of constant area, the velocity of flow of said gases will decrease as they cool. As will be seen, especially in Figures 1 and 2, the inner portion 10 of my heater, which provides a passage for conducting the flue gases or products of combustion from the fireplace portion or combustion chamber 11 to the stack 12, decreases gradually in passage area from the lower to the upper portion, and particularly that portion of the flue 10 in the intermediate section 3 of the heater where the greater amount of heat-transfer occurs.

In order to provide for conducting air to my heater for absorbing heat from the flue or central portion thereof, I desirably form the heater with outer walls 13 spaced from the walls of the flue 10 so as to provide a peripheral, annular, or at least partially enclosing conduit 14 therearound for receiving air to be heated. The area of the conduit or air passage 14 gradually increases upwardly to allow for the natural expansion of the air as heated and provides for substantially uniform velocity of said air, whereby said heated air tends to force itself out of the upper end of said passage. Into this conduit I direct air from outdoors, desirably through a screen 15, a passageway or air duct 16 communicating with the generally U-shaped lower portion 17 of the air compartment, illustrated most clearly in Figure 6. In order not to be obliged to take all of the air from outdoors, especially in severe weather, I provide for the recirculation of some of the air in the room, by forming one or more air intakes 18, the amount of air drawn therein being desirably controlled by shutters or dampers 19, one embodiment of which is illustrated in detail in Figure 9.

In order to efficiently utilize the heat of the fire, especially directly in the vicinity of the fuel 8 being consumed, I desirably provide a rigidifying bulge or corrugation 20 in that portion of the heater defining the back wall of the fireplace 11, which also prevents warping and provides a more durable construction. For further facilitating the transfer of heat from the flue 10 to the surrounding air heating space, the outer surfaces of the walls defining said flue and forming the inner surface of the air conducting chamber 14, and particularly the intermediate portions forming part of the heater element 3, are desirably corrugated or formed with heat-conducting ribs or fins 21, which, of course, rigidify the walls, prevent warping, and make the construction more durable.

To prevent substantial loss of heat from the air-conducting passageway 14 to the surrounding brickwork or masonry, the outer surface of the heater around the air passageway 14 is desirably covered with fire-proof insulation 22.

In order to hold the inner or waste gas flue 10 in position with respect to the outer or surrounding air flue 14 of the intermediate section 3, while not interfering with communication between all portions of the air-conducting flue,

upright webs 23 are shown for connecting said inner flue with the outer walls, said webs being shown as extending from the junctions at the front and side walls of the flue 10 to the side walls 24 of the heater section 3.

I show a damper 25 or adjustable baffle plate in the flue 10 above the air discharge portion 26 of the heater, said damper being controllable from one side of the fireplace, as by means of a rod 27 the inner end of which is pivoted to one arm of the bell crank 28, and the other arm of which is connected to an operating arm 29 rigid with the damper 25, by means of a connecting rod 30. Pushing in the rod 27 will move the damper 25 from the position shown in full lines to that shown in dot-dash lines, thereby controlling the amount of draft for the fire. I have found it undesirable to completely close the flue 10 by the damper 25, and, therefore, said damper does not extend the full width of said flue even when in closed position, as indicated in Figure 2. A desirable proportion is for the damper to close two-thirds of the flue area, thereby avoiding the possibility of checking the draft to an extent sufficient to cause smoking of the fire.

In order to control the flow of heat from the hot air discharge opening 26 to the room in which the heater is located, a damper 31, which may comprise shutters 32 as illustrated most clearly in Figures 1 and 2, is desirably provided. These shutters desirably swing outwardly and upwardly, so that, when partially open, the heated air tends to be deflected downwardly into the room rather than upwardly against the ceiling, in order to get the greatest useful heating effect from the hot air. The hot air discharge opening 26 is, of course, desirably larger than the aggregate area of the cold air receiving openings or passageways 16 and 18.

The operation of my improved fireplace heater is as follows:

When no fire is in the fireplace the dampers 19 and 31 are, of course, closed unless it is desired to keep them open for ventilating purposes. When a fire is in the fireplace, the waste gases pass into the relatively large lower end of the flue 10 and are discharged to the chimney or stack from the desirably smaller upper end thereof. The dampers or shutters 19 and 31 are adjusted so that the desired proportion of air is allowed to pass through the intakes 18 for mixing and recirculation with air from the outside, which is drawn into the heater through the screen 15 and passageway 16. The air striking the hot sides and back of the fireplace 11 expands and passes outwardly into the enlarged area around the ribbed portion 21 of the flue 10 completely surrounding said flue and receiving heat from all sides thereof. Dissipation of heat from the air being heated is desirably retarded by the insulation 22. The heated air finally passes from the annular or peripheral heating passage 14 into the upper or hood portion 4 of the heater, discharging through the single outlet 26 through the regulating shutters 31, at an angle to the direction of flue gas flow or in a substantially horizontal or diagonally downward direction.

A test of a heater involving my invention showed great efficiency in heating, not only the room in which the fireplace is located, but also communicating rooms, on account of the flow of air induced by discharging heated air in a generally horizontal or diagonally downward direction from above the fireplace and drawing air from the lower portion of the room adjacent said

fireplace, thereby utilizing a much greater proportion of the calorific value of the fuel for heating the room and house than has heretofore been possible with an open fireplace or former fireplace heaters not involving the scientific features of the present invention.

Although I have illustrated the embodiment of my invention as formed of cast iron, it is obvious that I do not wish to be limited to the material out of which it is formed or the exact proportions of the parts. The following claims allow for variations in design without departing from the spirit and scope of my invention.

I claim:—

1. In combination, a fireplace stack of generally uniform horizontal straight sided cross-section and serving as a form about which fireplace brickwork may be built, and an upwardly contracting waste gas flue mounted in said stack and

20 at least partially spaced from the inner surfaces thereof to leave an upwardly expanding air passage therearound, so that the air in said passage is allowed to expand as it is heated whereby to force itself out of the upper end of the passage, 25 while the waste gases in said flue correspondingly contract as they are cooled, and maintain approximately uniform velocity.

2. In combination, a fireplace stack of generally uniform rectangular cross-section and serving as a form about which fireplace brickwork may be built, and an upwardly contracting waste gas flue generally rectangular in horizontal section mounted in said stack and at least partially spaced from the inner surfaces thereof to leave an upwardly expanding air passage therearound, generally angular in horizontal section, so that the air in said passage is allowed to expand as it is heated, whereby to force itself out of the upper end of the passage while the waste gases in 40 said flue correspondingly contract as they are cooled, and maintain approximately uniform velocity.

3. In combination, a brickwork enclosed fireplace stack of generally uniform rectangular horizontal cross-section, and an upwardly contracting waste gas flue mounted in said stack and at least partially spaced from the inner surfaces thereof to leave an upwardly expanding air passage outwardly thereof, so that air in said pas-

sage may be heated from the waste gases in said flue and force itself out of the upper end of the passage while the waste gases correspondingly contract as they are cooled, and are maintained at approximately uniform velocity.

4. In combination, a fireplace stack of generally uniform rectangular horizontal cross-section and serving as a form about which fireplace brickwork may be built, and an upwardly contracting waste gas flue mounted in said stack and at least partially spaced from the inner surfaces of walls thereof to leave an upwardly expanding air passage therearound, and connected to intermediate portions of said walls by upright webs extending from junctions between said flue walls to corresponding side walls of said stack.

5. In combination, a fireplace heater of straight sided horizontal cross-section and serving as a form about which fireplace brick-work may be built, the lower portion of said heater being double walled on three sides and open on one side to provide a combustion chamber, the inner walls extending to form an upwardly contracting waste gas flue and the outer walls formed with laterally opening passages to admit air between said walls which form an upwardly flaring air warming space terminating in an opening for the discharge of heated air into a room, so that the air in said space is allowed to expand as it is heated and force itself out of said opening while the waste gases contract as they are cooled in the flue.

6. In combination, a fireplace heater of generally straight sided cross-section, having walls, and serving as a form about which fireplace brick-work may be built, and other walls forming an upwardly contracting waste gas flue generally straight sided in horizontal section mounted within said first-mentioned walls, and at least partially spaced from the inner surfaces thereof, to leave an upwardly flaring air passage generally straight sided in horizontal section, so that the air in said passage is allowed to expand as it is heated, whereby to force itself out of the upper end of the passage, while the waste gases in said flue correspondingly contract as they are cooled, and maintain approximately uniform velocity.

ROSS W. SNYDER.
